CLAIM

The ornamental design for an electrical transportation tool, as shown and described.

DESCRIPTION

FIG. 1 is a top, front, right perspective view of an electrical transportation tool, showing my new design;

FIG. 2 is a bottom, rear, left perspective view thereof;

FIG. 3 is a bottom, right perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

Contrast in materials is shown using line shading on some surfaces and stippling shading on others.
